UNITED STATES PATENT OFFICE.

CHARLES EDWARD POINTON AND JOHN EDWARD POINTON, OF WELLINGTON, ENGLAND.

MACHINE FOR MOLDING DOUGH OR LIKE MATERIAL.

SPECIFICATION forming part of Letters Patent No. 597,088, dated January 11, 1898.

Application filed February 25, 1897. Serial No. 625,022. (No model.)

To all whom it may concern:

Be it known that we, CHARLES EDWARD POINTON and JOHN EDWARD POINTON, residing at Wrekin Road, Wellington, in the county of Salop, England, subjects of the Queen of Great Britain, have invented certain new and useful Improvements in Machines for Molding Dough or Like Material, of which the following is a specification.

10 This invention consists of improvements relating to machinery for molding dough or like material, our object being to provide simple means whereby the molding shall be more efficiently performed than with the machines 15 or appliances at present in use.

We will describe our invention by reference to the accompanying sheet of drawings, to be hereinafter referred to.

Figure 1 is a side elevation, with part in section, of a dough-molding machine constructed in accordance with our invention. Fig. 2 is a sectional end elevation of the machine. Fig. 3 is a section to a larger scale through one of the annular molding-chambers.

25 The same reference-letters in the different views indicate the same parts.

We employ a pair of wheels, such as A A', which we mount upon a shaft B, with an intermediate or central collar C between them, 30 such collar being either formed with or attached to the shaft. The wheels A A' are secured to the shaft B by means of feather-keys or in such other manner that while they are compelled to rotate with the shaft, yet, when 35 necessary for cleaning purposes, they may be caused to slide along the shaft away from each other and be pushed back into position again after cleaning. The perimeters of the wheels are inclosed by the casing D, and the shaft 40 B is supported by the bearings mounted on the standards E E'.

During the working of the machine lateral movement of the wheels is prevented by the central collar C and by the studs F F', which 45 are screwed into the boss of the wheel A', as illustrated at Fig. 2, and cotter pins or pegs passing through the projecting outer ends of the studs. In this manner the two wheels are 50 tied together and retained in their working position against the central collar C. To slide the wheels out from the casing D, we

withdraw the cotter pins or pegs from the studs, thus disconnecting the wheels and permitting of their outward movement in opposite directions, sufficient space G being provided between the outer side of each wheel and the inner sides of the standards E E' to enable each wheel to be drawn out clear of the casing D for the thorough cleaning of the working surfaces of the machine. The wheels 60 are readily connected together again by simply pushing them back against the central collar and afterward inserting the cotter pins or pegs through the projecting outer end of the studs. We provide holes or slots, such as a a', in each wheel for the insertion of suitable draw-bars, by which the wheels can be readily drawn or pushed along the shaft.

The shaft B and the wheels A A' mounted thereon are caused to revolve together in the 70 same direction by hand or mechanical power applied or transmitted to the shaft in any suitable and well-known manner.

The dough to be molded is admitted to the annular molding-chambers H H' and discharged therefrom by way of the double-mouthed apertured attachment J, the admission-apertures being at the lower side J' and the discharge-apertures at the upper side J".

We find that the proper and efficient work- 80 ing of the dough depends chiefly upon the correct proportions and arrangement of the frictional or working surfaces formed by the rims of the revolving wheels A A' and the interior of the fixed casing D, which together 85 form the annular molding-chambers.

It will be understood that the two chambers H and H' have no connection or communication with each other, each being independent of the other, although the two rotating working surfaces formed by the wheels 90 of course move together.

We find after long and costly experiments that the correct form of the molding-chambers is as shown at the sectional view Fig. 3. 95 The surface A" of the wheel is struck from a radius K, which is rather greater than the depth L of the chamber. The stationary working surface of the inner projecting rib D' of the fixed casing D is struck from a radius K' equal to the radius K. The bottom of the chamber is of a form corresponding to

the arc of a circle whose center is at M, or the point where a line joining the inner extremities of the rim cuts the center line N O. The inner corner or angle P is well rounded, as shown, to prevent lodgment of particles of the dough that occurs without such rounding. The working surface of the wheel is extended beyond the center line O N for a distance Q, which varies with the nature of the dough and the amount of working required. Without such extension the dough would have a simple rotary motion imparted to it while being carried around the annular molding-chamber; but by the provision of the extension an additional turn or twist is imparted to the dough, and it is thus subjected to an additional kneading or like action.

Having now described our invention, what we claim as new, and desire to secure by Letters Patent, is—

1. In machinery for molding dough and like material the combination of the wheels A A' mounted upon and rotating with the shaft B, with a fixed casing D having internal projecting ribs D' which in conjunction with the rims of the said wheels A A' form the an-

nular molding-chambers H H', substantially as set forth.

2. In machinery for molding dough and like material the combination of the sliding wheels A A' connecting-bolts F F', shaft B having a central collar C and fitted with feather-keys, with the fixed casing D having internal projecting ribs as D' and provided with a double-mouthed apertured attachment J, substantially as set forth.

3. In machines for molding dough and like material the combination with a wheel A having a rim of the form of a quarter-circle with an extension Q beyond the center O N, of a casing D, having an internally-projecting rib D' which together with the rim of the said wheel A forms an annular molding-chamber, substantially as set forth.

In witness whereof we have hereunto set our hands in presence of two witnesses.

CHARLES EDWARD POINTON.
JOHN EDWARD POINTON.
